UNITED STATES PATENT OFFICE

112,277

DESIGN FOR A BOTTLE

Royden A. Blunt, Baltimore, Md.

Application August 27, 1938, Serial No. 79,598

Term of patent 14 years

To all whom it may concern:

Be it known that I, Royden A. Blunt, a citizen of the United States, residing at Baltimore, in the State of Maryland, have invented a new, original, and ornamental Design for a Bottle, of which the following is a specification, reference being had to the accompanying drawing, forming part thereof, in which:

The opposite side of that shown in the drawing is plain.

I claim:

The ornamental design for a bottle, as shown and described.

ROYDEN A. BLUNT.
